UNITED STATES PATENT OFFICE.

GIORGIA SANTOSTEFANO DELLA CERDA, OF VIAREGGIO, ITALY.

ELECTRIC-LIGHT SWITCH.

1,253,147.

Specification of Letters Patent.

Patented Jan. 8, 1918.

Application filed April 16, 1914. Serial No. 832,342.

To all whom it may concern:

Be it known that I, GIORGIA SANTOSTEFANO DELLA CERDA, subject of the King of Italy, residing at No. 79 Via S. Martino, 5 Viareggio, Italy, have invented certain new and useful Improvements in Electric-Light Switches, of which the following is a specification, reference being had therein to the accompanying drawing.

10 In electric light installations, and particularly in house installations, in the circuit is commonly inserted a switch, by means of which the lamps are lighted only in case of want, thus avoiding a useless and economically inconvenient waste of electric energy. It often happens that the consumers of electric light are aware of the position of the switches, and also in the dark they know quite well where they are; nevertheless it 15 frequently occurs that somebody is ignorant of that position, wherefore it may be convenient to make use of a signalizing means enabling to reach the switches also in the dark. This means is provided by the present invention, which consists in the employment of electrical switches provided with phosphorescent and luminous substances.

The means hitherto proposed to render electric switches visible in the dark are all 20 connected to the movable parts of the switch and therefore they may quickly deteriorate, while the appliance according to the present invention is situated in the interior of the switch and protected by the lid of the same. 25 In the annexed drawing is represented as an example an embodiment of the present invention; this embodiment refers to a novel switch, and is illustrated in Figures 1 and 2, of which—

30 Fig. 1 is a front view, and

Fig. 2 a section on line A—B of Fig. 1.

With reference to Figs. 1 and 2 the switch has a porcelain base —a—, in which is fixed

the pivot —b—, at the upper end of which by means of the plug —d— is fastened the 45 ebonite handle —c—, by the aid of which is caused to turn the drum —e— carrying the conducting plates which are to come into contact with the other conducting plates carried by the terminals —f—. On the base 50 —a— is applied a disk —h— formed of a luminous or phosphorescent substance, as for instance radiumized zinc or the like phosphorous substance; the said disk is protected by a glass globe —k— which, while it does 55 not prejudice the luminosity of the disk, protects also the switch, and serves particularly to insulate the inner contacts.

Instead of the disk —h— one may make use of a layer of phosphorescent varnish, or 60 of a ring filled with luminous powder, having care that the outer face of said ring be transparent, or of any other suitable means. It is to be noted that the phosphorescent layer is independent from the movable parts 65 of the switch.

The luminous substance may be renewed when its luminosity has greatly weakened.

Having now fully described this my invention, and how the same is to be carried 70 out, I declare that what I claim is:

A luminous electric light switch comprising in combination a base, a luminous substance applied to the outer surface of said base, a rotating drum on the central part of 75 the luminous layer, a rod intended to turn the drum, a glass globe covering the said luminous layer, and a handle outside the glass globe intended to present a means for turning said drum. 80

In testimony whereof I affix my signature in presence of two witnesses.

GIORGIA SANTOSTEFANO DELLA CERDA.

Witnesses:

CARLO FAROING,
A. P. CORDERO.
